UNITED STATES PATENT OFFICE.

RICHARD BRADSHAW, OF MONTREAL, QUEBEC, CANADA, ASSIGNOR TO SIMMONS COMPANY, OF KENOSHA, WISCONSIN.

BED-BOTTOM FABRIC.

Application filed July 2, 1925, Serial No. 41,176, and in Canada September 13, 1924.

This invention relates to improvements in bed bottom fabrics, and particularly to fabrics of the type comprising a number of parallel spaced strands and means for holding the strands in parallelism, and the object of the invention is to provide a durable, efficient and inexpensive bed bottom which may be manufactured and sold at a moderate price.

10 A further object is to provide means for holding the strands of a bed bottom normally in parallelism, while at the same time providing a sufficiently yielding structure for comfort.

15 A still further object is to provide a structure comprising a relatively small number of parts providing a large supporting surface for a mattress.

The invention consists essentially in the 20 provision of a bed bottom comprising a series of flat strands or ribbons of metal arranged edge to edge substantially in parallelism, and bent or twisted in one or both edges at intervals to provide laterally facing bearing surfaces materially wider than the edges of the strands and disposed in lines at right angles to the length of the strands. A series of spacing means, preferably helical springs, are disposed to have 25 abutting relation with the bearing surfaces of the strands with the helices thereof engaging between the bent or twisted edges of the strands and being held in position by locking wires extending through the springs 30 and through apertures near the edges of the strands.

In the accompanying drawings which illustrate the preferred form of the invention:—

40 Fig. 1 is a fragmentary plan view of a bed bottom.

Fig. 2 is a fragmentary plan view of the bed bottom on an enlarged scale as seen from below.

45 Fig. 3 is a fragmentary side elevation of one of the strands, showing the relative position of the strands, spring and locking wire.

Fig. 4 is a cross section on the line 4—4, 50 Figure 2.

Fig. 5 is a fragmentary plan view of a portion of a strand before bending.

Referring more particularly to the drawings, 11 designates one of two end members

of a bed bottom frame rigidly spaced apart 55 by any means (not shown). A fabric is stretched between the end members and comprises a series of flat strands or ribbons of metal, designated 14 and 15. The strands 14 are somewhat wider than the strands 15 60 and are disposed only at the edges of the structure. These strands are arranged in parallelism and connected at their ends to the end rails by any suitable means, such as helical springs 16. When in the flat the 65 strands 15 are provided at intervals with apertures 17 disposed adjacent the edges of the strands, the apertures being in line transversely of the strands, as clearly shown in Figure 5. The strands are then bent or 70 stamped to channel or U-shape form in the apertured portions thereof, as clearly shown at 18 in Figures 2, 3 and 4, so as to bring the holes 17 axially in line. The strands when thus formed are arranged in parallelism with the channelled portions thereof in line transversely of the strands and helical springs 19 are pressed against the channelled portions so that one or more turns 75 of the springs enter tightly into the channelled portion of each strand. The springs 19 may be, and are preferably, continuous from side to side of the structure, or may be a series of shorter springs arranged end to end. Preferably the outer extremities 80 of the springs are connected to the strands 14. Finally, locking wires 20 are passed through the springs and through the apertures 17 of the strands to hold the springs 85 against escape from the channelled portions 90 of the strands, and also to hold the springs tightly in place so that the structure will not give out a clicking or rattling sound when in use. The ends of the wires 20 are fastened in any suitable way to prevent 95 them working out. Preferably the wires 20 extend from side to side of the structure but shorter wires may be used.

The completed fabric thus formed is disposed in the frame with the channelled sides 100 of the strands turned downwardly, so that the upper or mattress supporting surface is smooth and free from sharp projections which might wear or tear a mattress. For all practical purposes the surface is flat, as 105 the slight elevations caused where the strands are channelled are very gradual and by actual measurement only a small

fraction of an inch. The thin wide strands provide a large supporting area without accompanying great weight. The springs hold the strands normally in parallelism and against such separation as would permit a mattress to pass appreciably between them. At the same time, the springs provide a yielding connection between the strands, enabling them to move sufficiently so that the structure is comfortable but always returns by reason of the spring action to a flat surface. The springs, being tightly wedged in the channelled portions of the strands, will not click or rattle in use. The whole structure is composed of a relatively small number of parts of inexpensive construction, so that the material and labour costs are low and the bed bottom may be manufactured and sold at a reasonable price. While the foregoing description presents the preferred embodiment of the invention, it will be understood that a number of modifications or alterations may be made without departing from the spirit of the invention. The purpose of forming the strands to channel shape is primarily to present bearing surfaces for the springs 19, which form strand spacing means. It will therefore be understood that the number of helices of the spring engaged in the channels is immaterial, also that it is not essential for there to be any tight engagement of the springs in the channels, since if the channel walls tightly engage between adjacent helices of the springs the same purposes will be served. It will also be readily seen that the channel shaped part may be so narrow as to be entirely closed and the two walls brought in contact with one another and engaged between adjacent helices of the springs, or that the strands may be bent at one edge only and yet provide laterally facing bearing surfaces and parts tightly engageable between adjacent helices of the springs. In the channelling, the strands are bent from their normal plane through approximately 90°, part of the width of the strand in one direction and part of the width in the opposite direction. It will be understood, however, that the entire width of the strand may be twisted at one time and in one direction through approximately 90°. Other forms of spacing means may be used. From the foregoing it will be readily understood that numerous modifications may be made and that all such modifications as fall within the scope of the appended claims are deemed to be included in the present invention.

Having thus described my invention, what I claim is:—

1. A bed bottom fabric comprising a series of solid flat ribbon-like strands disposed edge to edge and distorted at intervals in their length to present laterally facing bearing

surfaces, and spacing means disposed between the strands and engaging the adjacent bearing surfaces thereof.

2. A bed bottom fabric comprising a series of substantially parallel solid flat ribbon-like strands disposed edge to edge and formed at intervals in their length to present laterally facing bearing surfaces materially wider than the thickness of the strands, and resilient spacing members disposed between the strands and engaging said bearing surfaces. 75

3. A bed bottom fabric comprising a series of substantially parallel flat strands disposed edge to edge, the said strands being formed to channel shape at intervals in their length to present laterally facing bearing surfaces materially wider than the edges of the strands, and helical springs disposed transversely of the strands having the helices thereof at intervals engaged in the channel-shaped portions of the strands and abutting the laterally directed bearing surfaces of the strands. 80

4. A bed bottom fabric comprising a series of flat strands arranged edge to edge and formed at intervals in their length to present laterally facing bearing surfaces and apertured in such surfaces, spacing members between the strands engaging the bearing surfaces thereof, and means passing through the strand apertures holding the spacing means in operative relation with the strands. 90

5. A bed bottom fabric comprising a series of substantially parallel flat strands arranged edge to edge, said strands being formed to channel shape at intervals in the length thereof and apertured at their edges in such channel-shaped portions, and helical spring disposed transversely of the strands and having the helices thereof engaging in the channel-shaped portions of the strands, and locking wires passing through said springs and through the strand apertures and holding the springs against disengagement from the strands. 100

6. A bed bottom fabric comprising a series of substantially parallel flat strands arranged edge to edge, said strands being folded at intervals about their longitudinal axes to present laterally facing bearing surfaces appreciably wider than the edges of the strands and apertured in such folded portions, spacing members disposed between the strands in abutting relation with the bearing surfaces, and means passing through the strand apertures and holding the spacing means in operative relation with the strands. 115

7. A bed bottom fabric comprising a series of substantially flat strands arranged edge to edge, spaced portions of said strands being displaced from the plane of the strands to lie in planes substantially per- 120

pendicular thereto, the displaced portions of said strands being apertured, spacing means disposed between the strands in engagement with the displaced portions thereof, and holding means for said spacing means passing through the strand apertures.

8. A bed bottom fabric comprising a series of substantially flat strands arranged edge to edge, spaced portions of said strands being displaced from the plane of the strands to lie in planes substantially perpendicular thereto, the displaced portions of said strands being apertured, and helical springs disposed transversely of the strands and embracing the displaced portions of the

strands between adjacent helices, and locking wires passing through said springs and through the strand apertures.

9. A bed bottom fabric comprising a series of substantially parallel flat strands disposed edge to edge, the said strands being formed to channel shape at intervals in their length to present laterally facing bearing surfaces materially wider than the edges of the strands, and spacing members disposed between the strands and abutting the adjacent bearing faces thereof.

In witness whereof, I have hereunto set my hand.

RICHARD BRADSHAW.
